The ornamental design for a status indicator light, as shown and described.

DESCRIPTION

FIG. 1 is a perspective view of a status indicator light showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is second perspective thereof;

FIG. 9 is third perspective thereof; and,

FIG. 10 shows the status indicator light in a position of use with a broken line environment.

The dashed broken lines in the drawings illustrate portions of the status indicator light that form no part of the claimed design. The dot-dash broken lines represent the boundary of the claimed design, and the surface within the dot-dash broken lines are claimed.
